DOBBIES FOR LOOMS

Frank Davies and John Kennedy Pitts, Didsbury, Manchester, England, assignors to The British Cotton Industry Research Association, Manchester, England, a British association

Application November 6, 1952, Serial No. 319,044
14 Claims. (Cl. 139—71)

This invention relates to double-lift open-shed dobbies for looms and is particularly but not exclusively applicable to positive knife dobbies.

It is usual for positive knife dobbies to have an oscillating baulk moving in a vertical plane and the movements of which control the movement of the warp, through the intermediary of pivoted jacks to one end of which the baulks are pivotally attached and to the other end the heald shafts are connected. The oscillatory movement of the baulks is effected by oscillating knives which are adapted selectively to be engaged by hooks also movable in a vertical plane and pivoted to the ends of the baulks. The control of the hooks to bring them into engagement or disengagement with the oscillating knives is effected by feelers which in turn are under the control of a pattern chain mechanism. It is also common practice for the feelers and associated pattern chain mechanism to be located "inside" the dobbies mechanism i. e. forward of the baulk and with the feelers engaging the hooks intermediate of their pivots and the knife-engaging portions, thereby necessitating the use of long 35 hooks, resulting in a substantial overall length of the dobbies mechanism. Further, the backward movement of each baulk is limited by two back stops so that the baulk can rotate about either of its ends if such end is against its back stop or it can rotate about its mid-point if the baulk is in its forward position. An essential of such positive knife dobbies is that when required to do so the hooks should pivot quite freely to engage the knives to provide the interengaging necessary, to enable the knives to oscillate the baulks. Under certain conditions the free movement of the hooks is prevented because if the hooks are held against the front stops as is usual when the hooks are in their inoperative position, clear of the knives, and the warp tension on the jacks is such as to cause pressure against the front stops, the frictional force may be sufficient to prevent free fall of the hooks. This latter problem has been met by using additional mechanisms to relieve the pressure of the hooks on the front stops.

The object of the present invention is to provide an improved and simplified construction of dobbies mechanism wherein the use of long hooks and additional mechanism for relieving the pressure on said hooks is eliminated, whereby the mechanism for controlling the hooks from the pattern barrel is simplified and as a result can be housed in a smaller space.

The present invention comprises a double lift open-shed dobbies including two oppositely oscillating knives or griffes and a plurality of baulks each having a hook pivotally attached to each end thereof and by means of which said baulks are oscillated by the knives to effect shedding of the warps through heald levers by which the baulks are carried, wherein the baulks are arranged at the side of the knives remote from the warps and wherein each of said hooks is fashioned with the knife engaging portion on the side of its pivot which is nearer to the warp threads and has an extension or tail at

the other side of its pivot for engagement with pivoted feeler levers controlled by a pattern chain mechanism located "outside" the dobbies mechanism.

Preferably the hooks are freely pivoted on the baulk, and the knife-engaging portion is also fashioned with front stop-engaging formations, so that said portion can be made relatively short in length.

In the accompanying drawings:

Fig. 1 is a side elevation of one jack and associated operative parts of a double lift open shed positive dobbies constructed in accordance with the invention;

Fig. 2 is a section on the line 2—2, Fig. 3 and illustrates the driving mechanism for the oscillating knives or griffes of the improved dobbies and also shows the drive 15 to the pattern mechanism;

Fig. 3 is a part sectional end elevation on the line 3—3 Fig. 2.

Fig. 4 is a section on the line 4—4, Fig. 6, illustrating how the feelers are controlled by the pattern chain.

Fig. 5 is a section on the line 5—5, Fig. 6, and showing the means for locating the hooks of all the baulks in a neutral position when the loom is stopped with the warp shed closed.

Fig. 6 is an end view of Fig. 5 looking from the right.

Fig. 7 is a detail view of the means illustrated in Figs. 5 and 6.

In the drawings, and referring particularly to Fig. 1 thereof, the jack 10, of which there are several according to the number of heald shafts of the loom, is rotatably mounted in known manner on stationary shaft 11, and on the stud 11a carried by said jack is pivotally mounted a baulk 12, the upper and lower ends of which abut the upper and lower back stops 13, 14 when the baulk and jack are in the illustrated backward position. To the upper and lower ends of each baulk are freely pivoted upper and lower hooks 15, 16. The ends of the baulk are fashioned with bosses 12a and 12b adapted to contact the back stops 13, 14 and also to be engaged by upper and lower knives or griffes 17, 18, as they move rearwardly without interfering with the free pivotal movement of the hooks as will be later explained. The baulks are arranged at the side of the knives remote from the warps, and the inner or forward or warp side portion 15a of the upper hook 15 of each baulk is comparatively short and is rabbeted or notched at 15b to enable said hook to engage the upper front stop 19 when said hook is in the raised backward position as illustrated in Fig. 1. The hook 15 which is mounted on pivot pin 15x is also cut-away at 15c to provide means whereby, on pivotal movement, it can engage the upper knife or griffe 17. The upper hook 15 is also fashioned with a downwardly and rearwardly projecting portion or "tail" 15d on the opposite side of pivot 15x from the hook portion 15a, and abutting the upper face of said tail is the upper end 21b of a feeler 21, comprising a bell-crank lever pivotally mounted on shaft 22. The lower arm of the feeler is substantially vertical and has a cam face 21a which is adapted to be engaged by one of the pegs 23 mounted on a pattern chain 24 of a pattern barrel 24x forming part of a pattern mechanism located "outside" the dobbies mechanism. The inner or forward portion 15a of the hook 15 is heavier than the "tail" portion 15d, so that the hook is loaded to tilt in a clockwise direction to disengage from the front stop and engage the knife 17 if and when the feeler 21 will allow same so to do as dictated by the pattern chain (see Fig. 4).

The lower hook 16 pivoted at 16x to the lower end of the baulk 12 is somewhat similar in construction and operation to the upper hook 15, and also has a comparatively short, inner or forward portion 16a having a rabbet or notch 16b to engage the lower front stop 20, and

hook 16 is also cut away at 16c to receive and engage the lower griffe or knife 18. In addition to the outer portion or "tail" 16d, the lower hook has a weighted portion 16e, whereby it is caused to tilt on its pivot 16x in a counterclockwise direction to disengage from the lower front stop 20 and engage the knife 18 from underneath under the control of bell-crank feeler 26 pivoted on shaft 26b. The upper end of the vertical limb of the bell-crank feeler 26 has a cam face 26a adapted to be engaged by another peg of the pattern mechanism in manner similar to the cam face 21a of the feeler 21 for the upper hook. The feelers 21 and 26 are spring-loaded into engagement with the pegs of the pattern mechanism, by a spring 27 extending between them forwardly of their pivots 22 and 26b, respectively.

As illustrated in Figs. 2 and 3, the upper griffe or knife 17 extends between and is flexibly mounted on the upper ends of a pair of bell-crank levers 28, 28a pivoted at 29, 29a the said levers being located at each side of the machine with the knife 17 extending transversely across all the upper hooks. The proportions of the bell-crank levers and the location of the pivots thereof are so arranged that the knife can move angularly in an arc substantially corresponding with that followed by the pivots of the upper hooks when the baulks are rotated about the centres of the pivots of the lower hooks. The lower knife or griffe 18 is similarly supported or carried by a pair of bell-crank levers 30, 30a pivoted at 31, 31a but the bell-crank levers 30, 30a are opposed with respect to the bell-cranks 28, 28a, and links 32, 32a connect the free ends of the bell-crank levers, so that if said levers are pivoted or moved angularly in a clock-wise direction, see Fig. 2, the upper knife 17 will move to the right while the lower knife 18 will move to the left.

It will be understood that the angular path of movements of the lower knife 18 substantially follows the arc of movement of the lower hooks during pivoting movement of the baulks about the centres of the pivots of the upper hooks.

In order to give the required angular movement to the bell-cranks, 28, 28a, 30, 30a and thereby oscillate the knives, the bell-crank levers are oscillated by cams. As shown in Fig. 2 for one side of the dobby, one of the arms of lever 30 is provided with a cam follower 33 rotatable on a stud 33x, said cam follower being located in a cam groove 34, fashioned in a cam 35 mounted on a cam shaft 36. Thus it will be seen that lever 30 is oscillated by cam 35 through cam follower 33 while the lever 28 is oscillated by the lever 30 through link 32. On the other side of the machine (see Fig. 3) the lever 28a is oscillated by a cam 35a mounted on shaft 36 and a cam follower 33a while the lever 30a is oscillated by the lever 28a through link 32a. The cam shaft is driven by a pair of bevel gears 37, 38, see Fig. 3, the bevel gear 38 being mounted on a driving shaft 39 driven in turn from the loom top shaft (not shown). The cam groove of each cam is so shaped that it will cause each griffe or knife in turn to relieve all the adjacent hooks from their front stops at the end of each inward traverse, and in conjunction with the flexible mounting of the knives will also provide for the requisite "slating" or staggering of the knives during their oscillating movement. For the latter purpose the cams are so shaped that one end of each knife is advanced relatively to the other end, so that the knife moves forwardly in an inclined position, but at each end of the stroke the knife occupies a non-inclined position.

Also mounted on the cam shaft 36 is the driving member 40 of a Geneva motion, the driving pins thereof being identified by the numerals 41 and 42. The driven member 43 of the Geneva motion is mounted on the pattern barrel shaft 44 and by the driving connection illustrated in Figs. 2 and 3 the knives 17, 18 are oscillated in timed relationship with the pattern control mechanism.

It is usual to operate several jacks by the dobby mechanism and each jack has its own baulk with upper and lower hooks. The cam grooves 34 oscillate the knives 17, 18 in known manner and the hooks 15 and 16 pivot into or out of engagement with their respective knives under control of the pivoted feelers 21 or 26 (see Fig. 4), to operate the jacks 10 in manner required to weave the desired pattern. The cam grooves 34 are so proportioned and shaped that the knives on the backward movement of their traverse, engage the bosses 12a, 12b, at each end of each baulk to move same a sufficient distance to relieve the hooks from the front stops 19, 20 whereupon free pivotal movement of the hooks can occur, by reason of their unbalanced construction, if allowed to do so by the feelers 21, 26. If a hook is prevented by the pattern chain (operating through the feelers) from engagement with its associated knife, then on outward movement of said knife the hook rests against the front stop.

It will be appreciated from the showing of Fig. 1 that the weighting or loading of the bottom hooks at their tail or rearward portions urges them to pivot to engage the lower knife 18 from underneath.

As is well known in the textile trade it is desirable when weaving artificial silk to close the shed and equalize the tension on the warp threads if and when the loom is stopped for any length of time, for example over-night, in order to prevent stretching of the said threads.

In the improved dobby construction, provision is made for closing the shed and reference is now made to Figs. 5, 6 and 7, wherein is illustrated means therefor. Said means comprises an upper rod 45 extending above and transversely of all the tails 15d of the upper hooks, and a lower rod 46 above and extending transversely of all the feelers 26, and said rods are supported by and between the upper and lower ends of a pair of bell-crank levers 47, 47 mounted on shaft 22 journaled in bearings 49, 49. In order to give the requisite pivotal movement to the shaft 22 to lower the upper rod 45 into contact with the tails of all the upper hooks to disengage them from the upper knife 17 and engage them with the upper front stop 19, an operating handle 50 is provided pivoted at 51, and at one end of said lever is an arcuate slot 52 in which is located a pin 53 fixed to the upper end of a substantially vertical arm 54 on the shaft 22. It will be appreciated that when the handle 50 is moved to the position indicated in dot-dash lines in Fig. 7, the pin 53 will be moved to the dotted position (Figs. 5 and 7), and consequently a partial angular movement will be imparted to the shaft 22 through the arm 54, and such movement will pivot the bell-crank levers 47 and cause the rod 45 to make contact with all the tails of the upper hooks and pivot them out of contact with the upper knife or griffe, thereby relieving simultaneously all the upper hooks and holding same free from engagement with the upper knife. Similarly and simultaneously the lower rod 46 is engaged with the lower feelers 26 and moves them to the dotted position, Fig. 5, allowing the bottom hooks 16 to rise for engagement with the lower knife 18.

It will be understood from the foregoing description that, as used in the specification and claims hereof, the terms "front," "forward" and "forwardly" have reference to that side of the dobby mechanism on which the warps are located, while "back," "backward," "backwardly" and "rearwardly" have reference to the side opposite that on which the warps are located.

What we claim is:

1. A double lift open-shed dobby for looms comprising a plurality of baulks each having an upper hook and a lower hook pivotally mounted on the upper and lower ends, respectively, of the baulk, upper and lower front stops adjacent the respective ends of the baulk for preventing forward movement of the hooks and of the associated supporting ends of said baulks, a pair of upper and lower oscillatory knives positioned forwardly of said

baulks and adapted to be selectively engaged by said hooks for oscillating said baulks to effect shedding of the warps when said hooks are disengaged from the front stops, means for oscillating said knives oppositely to one another, each of said hooks having a knife and front stop engaging portion extending forwardly, and a tail portion extending rearwardly, of its pivot, pivotally mounted feeler members in engagement with the tail portions of said hooks for controlling the pivotal movements of said hooks relative to said baulks, and a pattern mechanism for controlling the operation of said feeler members, both said feeler members and said pattern mechanism being positioned rearwardly of said baulks.

2. A double lift open-shed dobby according to claim 1 wherein the knife engaging portions of said hooks are relatively short and have notches formed therein for engagement with said front stops.

3. A double lift open-shed dobby according to claim 2 wherein the weight of each hook is so distributed relative to its pivot as to normally rotate the hook about its pivot in a direction to bring the knife engaging portion thereof into engagement with the associated knife, the ends of said baulks being provided with surfaces adapted to be engaged by the knives during the backward oscillatory motion of the latter so as to move said baulks rearwardly and relieve the notched portions of said hooks from frictional engagement with said front stops and thereby free said hooks for pivotal movement into engagement with said knives under the control of said feeler members.

4. A double lift open-shed dobby for looms comprising a plurality of baulks each having a hook pivotally mounted on each end thereof, a front stop adjacent each end of the baulk for preventing forward movement of the hooks and of the associated supporting movement of the hooks, a pair of oscillatory knives positioned ends of said baulks, a baulks and adapted to be selectively engaged by said hooks for oscillating said baulks to effect shedding of the warps when said hooks are disengaged from the front stops, means for oscillating said knives oppositely to one another, each of said hooks having a knife engaging portion extending forwardly, and a tail portion extending rearwardly, of its pivot, a pair of pivotally mounted feeler members positioned rearwardly of each baulk for controlling the pivotal movements of the hooks carried by said baulk, and a pattern mechanism also positioned rearwardly of said baulks for controlling the operation of said feeler members, each pair of said feeler members comprising oppositely arranged bell-crank levers adapted to pivot in opposite directions to engage the tail portions of their associated hooks, each of said bell-crank levers having one limb in abutment with the tail portion of the adjacent hook and another limb so positioned as to be engaged by said pattern mechanism.

5. A double lift open-shed dobby according to claim 4 including means for yieldably urging the limbs of said feeler members into engagement with the tail portions of said hooks and the pattern mechanism, respectively.

6. A double lift open-shed dobby according to claim 4 including a spring so interconnecting like limbs of each of said pairs of feeler members as to yieldably maintain said feeler members in engagement with the tail portions of their associated hooks.

7. A double lift open-shed dobby according to claim 1 including means tending to so rotate said hooks about their pivots as to bring the knife engaging portions thereof into engagement with said knives, the ends of said baulks having surfaces adapted to be engaged by said knives during the backward oscillatory movement of the latter and so disposed with respect to said hooks as to permit rearward movement of the baulks by said knives without interference with the pivotal movement of the hooks.

8. A double lift open-shed dobby according to claim 1 including means for raising all of the upper hooks into engagement with the upper front stop and simultaneously moving the feeler members of the lower hooks in such direction that said lower hooks are rotated into position for engagement with the lower knife, whereby the shed may be closed and the warp threads held as one sheet in any desired position.

9. A double lift open-shed dobby according to claim 8 wherein said hook raising and feeler member moving means comprises a pair of upper and lower transversely extending bars, and bell-crank levers for supporting said bars and moving the latter into engagement with the tails of the upper hooks and with the bottom feeler members, respectively.

10. A double lift open-shed dobby according to claim 1 wherein the means for oscillating said knives includes two sets of pivotally mounted levers to which the ends of said knives are connected, and a rotary cam mechanism operatively connected to each set of levers for oscillating said levers about their pivots.

11. A double lift open-shed dobby according to claim 10 wherein the cam mechanisms at the opposite ends of the knives are so constructed and arranged that one end of each knife is advanced relatively to the other during its movement, whereby the knives move into inclined positions and shedding is progressive across the loom.

12. A double lift open-shed dobby according to claim 11 wherein the cam mechanisms at the opposite ends of the knives are so constructed and arranged that at the end of the backward movement of said knives each knife occupies a non-inclined position uniformly disposed with respect to the hooks across the loom and with the forward end of the hooks disengaged from both the adjacent knife and front stop for free pivotal movement of the hooks under control of the pattern mechanism.

13. A double lift open-shed dobby according to claim 11 wherein said cam mechanisms include a cam shaft positioned between the baulks and the feeler members.

14. A double lift open-shed dobby for looms comprising a plurality of baulks each having a hook pivotally mounted on each end thereof, a pair of oscillatory knives adapted to be selectively engaged by said hooks for oscillating said baulks to effect shedding of the warps, means for oscillating said knives oppositely to one another, each of said hooks having a knife engaging portion and an extension on the side of its pivot remote from said knife engaging portion, the hooks at opposite ends of each baulk having their extensions directed towards one another and being so arranged as to engage the respective knives by rotation about their pivots in opposite directions, pivotally mounted, oppositely rotatable feeler levers operatively associated with the extensions of the hooks at opposite ends of each baulk for selectively controlling the rotational movements of said hooks about their pivots, and spring means for yieldably rotating said feeler levers in such directions as to urge said hooks out of knife engaging position.
